FISH LURE

Walter O. Wille, 1715 E. Altgeld, South Bend, Ind.

Filed Apr. 16, 1963, Ser. No. 74,462

Term of patent 14 years

(Cl. D31—4)

FIG. 2

FIG. 1

FIG. 3

FIG. 4

I claim:

The ornamental design for a fish lure, substantially as shown and described.
